CLAIM

The ornamental design for a compression device, as shown and described.

DESCRIPTION

FIG. 1 is a left perspective view of a design for a compression device supported on a band shown in phantom.

FIG. 2 is a left perspective view of the design shown in FIG. 1.

FIG. 3 is a front elevational view of the design shown in FIG. 1.

FIG. 4 is a rear elevational view of the design shown in FIG. 1.

FIG. 5 is a right side elevational view of the design shown in FIG. 1.

FIG. 6 is a left side elevational view of the design shown in FIG. 1.

FIG. 7 is a top plan view of the design shown in FIG. 1; and, FIG. 8 is a bottom plan view of the design shown in FIG. 1. The broken lines in FIG. 1 represent environment structure and form no part of the claimed design. The broken lines in FIGS. 3, 5 and 8 depict portions of the compression device that form no part of the claimed design.
